ROLLER CLAMP FOR FLEXIBLE TUBING AND THE LIKE

Channing W. Gilson, Los Angeles, Calif., assignor to
Don Baxter, Inc., Glendale, Calif., a corporation of
Nevada

Filed June 8, 1962, Ser. No. 70,479

Term of patent 14 years

(Cl. D54—13)

FIG. 1.

FIG. 4.

FIG. 2.

FIG. 5.

FIG. 3.

FIG. 6.

FIG. 7.

FIG. 8.

FIG. 9.

FIG. 1 is a bottom plan view of a roller clamp for flexible tubing and the like embodying my new design; FIGURE 2 is a side elevation of the roller clamp of FIGURE 1;

FIGURE 3 is a top plan view of the roller clamp;

FIGURE 4 is an end view taken from the left side of FIGURE 2;

FIGURE 5 is an end view taken from the right side of FIGURE 2;

FIGURE 6 is a top perspective view on a reduced scale, the roller being located in an alternate position;

FIGURE 7 is a cross-sectional view taken along line 7-7 of FIGURE 2;

FIGURE 8 is a cross-sectional view taken along line 8-8 of FIGURE 2; and

FIGURE 9 is a bottom perspective view on a reduced scale.

I claim:

The ornamental design for a roller clamp for flexible tubing and the like, as shown and described.
